R. KING.

CLASP FOR A RIBBON BRACELET.

APPLICATION FILED MAR. 4, 1920.

55,423.

Patented June 8, 1920.

FIG. 1.

FIG. 2.

INVENTOR.

Rufus King
Joseph A. Miller

ATTORNEY.

UNITED STATES PATENT OFFICE.

RUFUS KING, OF PLAINVILLE, MASSACHUSETTS, ASSIGNOR TO BUGBEE & NILES COMPANY, OF NORTH ATTLEBORO, RHODE ISLAND.

DESIGN FOR A CLASP FOR A RIBBON-BRACELET.

55,423.

Specification for Design.

Patented June 8, 1920.

Application filed March 4, 1920. Serial No. 363,324. Term of patent 7 years.

To all whom it may concern:

Be it known that I, RUFUS KING, a citizen of the United States, residing at Plainville, in the county of Norfolk and State of Massachusetts, have invented a new, original, and ornamental Design for a Clasp for Ribbon-Bracelets, of which the following is a specification, reference being had to the accompany drawings, forming part thereof.

Figure 1 is a view of the obverse side of the clasp, showing my design.

Fig. 2 is a sectional view of a portion of the clasp.

I claim

The ornamental design for a clasp for a ribbon bracelet, as shown.

RUFUS KING.

Witnesses:

H. A. GARDNER,
R. E. JACKSON.
